Attorney

UNITED STATES PATENT OFFICE.

DONALD B. BECKER, OF WATERVLIET, NEW YORK, ASSIGNOR TO GEO. P. IDE & COMPANY, INC., OF TROY, NEW YORK, A CORPORATION OF NEW YORK.

SOFT TURNDOWN COLLAR.

Application filed December 30, 1922. Serial No. 610,055.

To all whom it may concern:

Be it known that I, DONALD B. BECKER, a citizen of the United States, residing at Watervliet, in the county of Albany and 5 State of New York, have invented certain new and useful Improvements in Soft Turn-down Collars, of which the following is a description.

The main trouble with all two piece soft 10 collars heretofore made is that the upper part of the neck band, where the top portion of the collar folds over, has been too heavy.

The object of my invention is to provide a two piece soft turn down collar in which 15 the neck band is sufficiently heavy throughout the major portion of its area to be self supporting, but which is of such construction at its upper edge portion that the fold line of the collar is not too heavy, although 20 the neck band may be twice as heavy as the foldover top portion.

My invention consists of a collar in which the neck band comprises two separate plies adapted to be secured together by the usual 25 marginal stitching of the collar; each plie comprising a layer of comparatively heavy fabric and having a marginal binding stitched around its edges.

In the drawing: 30 The reference number 1 designates the top foldover portion of the collar, the lower and raw side edges of which are overseamed and then hemmed as at 2.

The neck band is composed of two plies 35 3 and 4 of comparatively heavy fabric the raw edges of which are bound by a tape 5, 6, respectively the tape being secured by means of the row of stitching 7, 8.

The lower edges of the plies 3 and 4 of the 40 neck band are secured together by means of the row of stitching 9. The upper raw edge of the foldover top 1 is then placed between the upper edges of the neck band plies 3 and 4 and the three pieces are then secured together by means of the row of stitching 10.

It will thus be seen that my invention provides a folding collar in which the fold line is not too heavy, notwithstanding the fact that the neck band is twice as thick as the foldover top portion.

If desired, the plies 3 and 4 may be further secured together by rows of stitching 11, 12, intermediate their top and bottom edges, said stitching running longitudinally of the band. By "comparatively heavy fabric" I mean a 55 fabric much heavier than the linen which is ordinarily used in the manufacture of collars.

What I claim is:

1. In a collar, a neckband comprising two separate plies adapted to be secured together 60 by the marginal stitching of the collar; each plie comprising a layer of comparatively heavy fabric and a marginal binding stitched around the edges of each plie connecting the bottom and end edges of the two plies together.

2. In a collar, a neckband comprising two separate plies adapted to be secured together by the marginal stitching of the collar; each plie comprising a layer of comparatively 70 heavy fabric and a marginal binding stitched around the edges of each plie and a plurality of rows of stitches securing said plies together intermediate the top and bottom edges of said plies and a marginal row of 75 stitching connecting the bottom and end edges of the plies together.

3. In a collar, a neckband comprising two plies of comparatively heavy fabric, a marginal binding stitched around the edges of 80 each plie, a plurality of rows of stitches securing said plies together intermediate the top and bottom edges thereof, a fold over top secured between the top edges of said neckband plies by stitching and a row of stitching 85 securing the bottom and end edges of the neckband together.

In testimony whereof I affix my signature.

DONALD B. BECKER.
